UNITED STATES PATENT OFFICE.

HENRY GRASS, OF FLOWERSDALE, VICTORIA.

FOUNTAIN-PEN.

SPECIFICATION forming part of Letters Patent No. 662,357, dated November 20, 1900.

Application filed September 27, 1900. Serial No. 31,293. (No model.)

To all whom it may concern:

Be it known that I, HENRY GRASS, a subject of the Queen of Great Britain and Ireland, residing at Flowerdale, near Broadford, 5 in the colony of Victoria, have invented certain new and useful Improvements in Fountain-Pens; and I do hereby declare the following to be a full, clear, and exact description of the invention, such as will enable 10 others skilled in the art, to which it appertains to make and use the same.

The object of this invention is to provide improvements in fountain-pens, including devices for feeding ink to nibs.

15 Among the defects of many existing fountain-pens is that the flow of ink too often becomes scanty, and it is not possible with them to make the same heavy ink-charged strokes upon paper which can be made with an ordinary nib supplied by dipping into any ordinary ink-well. In many fountain-pens, moreover, the ink is at times apt to accumulate and drop from the pen, so as to make blots. While the above-named scantiness is not a 20 bar to the use of the ordinary fountain-pen so long as it does not get out of order, yet the supply of ink to the nib being so small this feature detracts from the comfortable use of such pens in many hands. These defects are 25 preventable by the use of my invention, which enables the writer to produce bold heavy writing, to use any nib (of suitable size) he pleases, and to change the nib (without difficulty or danger of damaging the pen) when it 30 is no longer satisfactory. To secure these advantages, I attach to the pen-handle a movable attachment, which I term a "wad-cup," and to this is supplied a wad and ink, as herein-after set forth, and I also provide the handle 35 40 with an ink-reservoir, an ink-feed cup, and other features hereinafter explained. By having the wad-cup longitudinally movable the same can be adjusted more or less forward relatively to the nib-point, so as to increase or decrease the freedom of the flow of 45 ink to the said point, and the wad can be quickly changed and adjusted in position to a nicety without removing the nib.

In order now to further explain my invention, reference will be made to the accompa-

nying drawings, in which a pen containing the same is exhibited.

In Figures 1 to 3 the pen-point and adjacent parts are shown, and in Fig. 4 the other end. Fig. 1 is a longitudinal central section through 55 the device, showing the end for holding the pen-point. Fig. 2 is a plan of the under side of the device. Fig. 3 is a similar view of the top, and Fig. 4 is a longitudinal central section similar to Fig. 1, but showing the opposite end.

60 *a* is a hollow holder forming an ink-reservoir *t*, permanently closed at the base, except for an opening through which passes an ink-feed tube *p*, the exit of which is marked *d*. 65 The base *k* has a slit or other known means for the reception of the back end of a nib *b*; but this slit or means does not communicate with the interior *t* of holder *a*. The upper end of tube *p* is enlarged and forms an ink-feed cup *e*, which is situated at the head of the holder *a*. Beneath the nib *b* and forming with it and the base *k* a closed chamber *r* is a plate or wad-cup *f*, which preferably 70 is curved, as shown, and has wings, as *g*, which 75 fit above the nib-sides. Into this chamber, in which is the exit *d*, I place a piece of sponge or material *s*, capable of absorbing ink and of allowing the same to be drawn off in the action of writing. This piece of material I 80 call a "wad," and in Fig. 4 a spare one *s'* (ready for future use) is illustrated inside the movable cap *l*, which fits or screws on the head of holder *a*. The cap which protects the nib 85 when the latter is not in use is not shown, but will be well understood, and it forms no part of my invention.

To enable the wad-chamber to be opened to allow of the wad being removed or attended to, I make the cup *f* (or base of that chamber) 90 capable of sliding forward, the cup having integral therewith a strip *h* at its upper end and at the upper end of the strip a band *i*, encircling holder *a* and adapted to slide to and fro below the normal position shown in 95 the drawings. To hold the wad in place and prevent its shifting through any jolting of the pen, the wad-cup has several spikes *j*, usually formed by stamping or bending up part of the material of said cup. On these 100

spikes the wad is impaled in proper position, and when the band *i* is pushed toward the nib end the cup and wad together move forward clear of the said nib. I do not use a wad so large as to tightly fill the wad-cup, nor do I make the cup air-tight. In fact, the small apertures in the cup made when forming spikes *j* admit air beneficially. The cap *l* screws down and its piston *m* closes the reservoir *t* and the ink-cup *e* simultaneously. When, however, it is unscrewed a little, as seen in Fig. 4, the parts *t* and *e* are put in communication with one another.

The piston *m*, which is limited in its upward movement, as by a shoulder *n*, can be pushed forward and backward (when the cap *l* is partly unscrewed) by means of a push-rod *o*, which projects through the top of cap *l*. The piston-base has attached to it also a projecting wire *c*, by which the feed-tube *p* can be conveniently cleaned at will from either end and the flow of ink through the same insured.

In using this invention the ink-supply to the wad is intermittent—that is to say, a charge of ink is taken into the tube *p* from time to time, as required by the writer. To charge tube *p*, the cap *l* must be slightly unscrewed and the pen held with the nib uppermost for a short time. Some ink from reservoir *t* will then enter the cup *e* and tube *p*, and the said cup may thus be filled. If on holding the nib downward the ink does not run from the exit sufficiently to saturate the wad *s*, the piston *m* may be moved to and fro a few times, and this will force the ink down. By keeping the piston down (thus closing cup *e*) a further supply of ink in tube *p* is prevented by the air-pressure beneath from running too rapidly out of the same into the wad. After a little practice the management of the piston and the holding of the nib uppermost momentarily at intervals is easily effected, so as to feed a larger or smaller amount of ink to the wad, as required.

The chamber *u* above piston *m* in the cap *l* is provided for convenience to keep a supply of spare wads in, as in course of time the wad in use becomes charged with solid matter and needs renewal. The wad should be approximately pointed with a broad rear end, into which the exit *d* should slightly project.

I may add that in carrying out my invention it may be modified in minor details without departing from its scope.

What I do claim as my invention, and desire to secure by Letters Patent of the United States, is—

1. In a fountain-pen of the class indicated, the handle having a reservoir with base *k* having a slit or the like therein for the nib, of an ink-feed tube *p* passing partly through said base and having its exit near the nib, the other end of said tube having an ink-feed cup *e*, and the said reservoir and tube having a screw-cap *l* with a movable piston *m*, all substantially as and for the purposes set forth. 60

2. In a fountain-pen of the class indicated, the combination with the handle having a reservoir, base, ink-feed tube with exit near the nib, and screw-cap as set forth, of a longitudinally movable and adjustable wad-cup, and a wad, all substantially as and for the purposes set forth. 70

3. In a fountain-pen of the class indicated, the combination with the ink-feed tube having its exit in a chamber under the nib, of the wad *s*, the wad-cup *f* having spikes *j* on which said wad is impaled, and a strip *h* extending from the said cup to a band *i* encircling and adapted to slide on the pen-handle, all substantially as and for the purposes set forth. 75

4. In a fountain-pen of the class indicated, the combination with the handle having a reservoir with ink-feed tube and ink-feed cup as set forth, of a screw-cap having a movable piston limited in its upward movement, and a push-rod, all substantially as and for the purposes set forth. 80

5. In a fountain-pen of the class indicated having an ink-feed tube and ink-feed cup, a screw-cap having a piston limited in its upward movement, a push-rod, and a projecting wire for cleaning the ink-feed tube, all in combination substantially as and for the purposes set forth. 90

6. In a fountain-pen of the class indicated having an ink-feed tube and ink-feed cup, a screw-cap having a piston limited in its upward movement, a push-rod, a projecting wire for cleaning the ink-feed tube, and a spare wad-chamber above the said piston, all in combination substantially as and for the purposes set forth. 100

In testimony whereof I affix my signature in presence of two witnesses.

HENRY GRASS.
